FOLDING FURNITURE

Ernest G. Covell, Springfield, Mo., assignor of one-half to Jesse W. Hogg, Springfield, Mo.

Application April 12, 1943; Serial No. 482,771

4 Claims. (Cl. 311—99)

The present invention relates generally to new and useful improvements in furniture, particularly tables, benches, et cetera, and has for its primary object to provide, in a manner as hereinafter set forth, devices of this character which, when not in use, are adapted to be expeditiously folded in a manner to require a minimum of space.

Another very important object of the invention is to provide a table or bench of the aforementioned character comprising novel means for firmly securing the supporting legs in open or operative position.

Other objects of the invention are to provide a folding table or bench which will be comparatively simple in construction, strong, durable, highly efficient and reliable in use, compact, light in weight, and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of a table constructed in accordance with the present invention.

Figure 2 is a bottom plan view of the table, showing the legs in folded or inoperative position.

Figure 3 is a view in end elevation, showing the table folded.

Figure 4 is a plan view of a corner portion of the table with the top broken away.

Figure 5 is a vertical sectional view, taken substantially on the line 5—5 of Figure 4.

Figure 6 is a vertical sectional view at right angles to Figure 5, taken substantially on the line 6—6 of Figure 4.

Referring now to the drawings in detail, it will be seen that the embodiment of the invention which has been illustrated comprises a pair of complementary half-sections 1 which are hingedly connected at 2. The half-sections 1, when in unfolded position, constitute the top of the table.

Each section 1 comprises a substantially rectangular apron which includes inner and outer side rails 3 and 4, respectively, and end rails 5. Each of the sections 1 further includes a top 6 of suitable material, such as plywood, mounted on the rails 3, 4 and 5. As illustrated to advantage in Figure 5 of the drawings, the upper,

inner portions of the rails 3, 4 and 5 are rabbeted, as at 7, for the reception of the marginal portions of the top 6.

Elongated blocks 8 are secured vertically on the end rails 5 adjacent to, but spaced from, the outer side rails 4. Pivot bolts 9 extend between the blocks 8 and the outer side rails 4. Folding legs 10 are journaled for swinging movement on the bolts 9 between the blocks 8 and the outer side rails 4.

Cam grooves 11 are provided in the outer side rails 4 adjacent the end rails 5. From their upper to their lower ends, the cam grooves 11 incline toward the end rails 5 (see Fig. 5). Retaining arms 12 for the legs 10 are pivotally secured at 13 on the blocks 8. The free end portions of the arms 12 are engageable in the cam grooves 11 in a manner to be wedged thereby against the opposed faces of the unfolded or open legs 10 for firmly securing said legs in open position. As also shown to advantage in Figure 5 of the drawings, the sides of the arms 12 which are remote from the open legs 10 are beveled to conform to the inclination of the cam grooves 11.

It is thought that the manner in which the invention functions will be readily apparent from a consideration of the foregoing. Briefly, when the table is not in use, the legs 10 are folded into their respective sections 1 and said sections 1 are

swung to closed position on the hinges 2 substantially in the manner of a suitcase, as seen in Figure 3 of the drawings. When the table is to be used, the sections 1 are opened on the hinges 2 and the legs 10 are swung to open position against the end rails 5. The arms 12 are then engaged in the cam grooves 11 and wedged between the legs 10 and the side walls of said grooves which are remote from said legs. Thus, the legs 10 are firmly secured in open position.

However, the construction and arrangement is such that the arms 12 may be easily swung upwardly out of the grooves 11 when it is desired to fold the legs 10.

It is believed that the many advantages of a folding table or bench constructed in accordance with the present invention will be readily understood, and although a preferred embodiment of the device is as illustrated and described, it is to be understood that changes in the details of construction and in the combination and arrangement of parts may be resorted to which will fall within the scope of the invention as claimed.

What is claimed is:

1. A table comprising an apron including end and side rails, a top mounted on the rails, the side

rails having cam grooves therein, pivot bolts mounted on the side rails adjacent the grooves, folding legs journaled on said pivot bolts, said grooves and legs extending in the same general direction when the legs are open, and said grooves including a wall inclined downwardly in a direction toward an adjacent open leg, and arms pivotally mounted on the end rails for retaining the legs in open position, said arms having free ends adapted to travel in the cam grooves in engagement with the inclined wall thereof to force the arms against the legs and to force the legs against an adjacent end rail.

2. A table of the character described comprising an apron having substantially vertical cam grooves therein, a top mounted on the apron, folding legs mounted for swinging movement on the apron, said grooves and legs extending in the same general direction when the legs are open, and said grooves including a wall inclined downwardly in a direction toward an adjacent open leg, and arms pivotally mounted on the apron and having free ends adapted to travel in the grooves in contact with said inclined wall for wedging of the arms against the legs for retaining said legs in open position.

3. A table comprising an apron including side and end rails, said side rails having substantially vertical cam grooves therein adjacent said end rails, blocks on the end rails adjacent to, but spaced from, the side walls, pivot bolts extending between the side rails and the blocks adjacent the grooves, supporting legs journaled on the pivot

bolts for swinging across the grooves, said grooves and legs extending in the same general direction when the legs are in open position and said grooves including a wall inclined downwardly toward an adjacent open leg, and arms pivotally mounted on the blocks and having free ends adapted to travel in the cam grooves in contact with said inclined wall to guide the arms against the legs for forcing said legs against the end rails for firmly securing said legs in open position.

4. A table of the character described comprising a pair of hingedly connected half-sections, said sections comprising inner and outer side rails and end rails, said sections further including tops mounted on the rails, the outer side rails having substantially vertical cam grooves therein adjacent the end rails, blocks mounted on said end rails adjacent to, but spaced from, the outer side rails, pivot bolts extending between said outer side rails and blocks adjacent the grooves, folding supporting legs for the sections journaled on the pivot bolts for swinging across the grooves, said grooves and legs extending in the same general direction when the legs are in open position and said grooves including a wall inclined downwardly toward an adjacent open leg, and arms pivotally mounted on the blocks and having free ends adapted to travel in the cam grooves in contact with said inclined wall to guide the arms against the legs for securing said legs in open position against the end rails.

ERNEST G. COVELL.
